Patented Aug. 30, 1921.

Inventor,
Edmund Bruder:

By E. Edmund Bruder

UNITED STATES PATENT OFFICE.

EDMUND BRUDER, OF CHICAGO, ILLINOIS.

DESIGN FOR A GAME-DIAL OR SIMILAR ARTICLE.

58,707.

Specification for Design.

Patented Aug. 30, 1921.

Application filed June 2, 1921. Serial No. 474,570. Term of patent 7 years.

To all whom it may concern:

Be it known that I, EDMUND BRUDER, a citizen of the United States, residing at Chicago, in the county of Cook and State of Illinois, have invented a new, original, and ornamental Design for a Game-Dial or Similar Article, of which the following is a specification, reference being had to the accompanying drawing, forming a part thereof.

The figure is a view of a game dial or similar article showing my new design.

I claim—

The ornamental design for a game dial or similar article as shown.

EDMUND BRUDER.
